PORTABLE COOLER, GASSER, AND DISPENSER FOR KEG BEER AND THE LIKE

George Craig Woolley, St. Paul, Minn.

Application September 24, 1956, Serial No. 611,463

2 Claims. (Cl. 62—306)

This invention relates to a readily portable device for supporting and completely servicing a keg or small barrel of beer or other beverage which requires for proper draught and taste characteristics, cooling, gassing and controlled dispensing. My present invention is particularly designed and conceived for home rather than commercial use where it is desired to dispense a draught beverage such as beer to a group of people, from a keg.

At the present time the distributors of various malt beverages supply to their customers, cooling and gassing apparatus for small gatherings, usually employing a helical coil to be placed in a box of ice and an air pump or carbon dioxide cylinder of heavy construction. The apparatus is hooked up at the home and in many instances, the keg heats up (since only the discharge through the coil is cooled), the saturation level of the gas is consequently decreased in the beer and more gas is released, resulting in foam when the beverage is dispensed. The coil, if not thoroughly cleaned and sterilized after each use, is unsanitary and gives the next user an off-taste beer. Cleaning time of such coil requires from a half to a full hour and is often disregarded by the distributor.

It is an object of my invention to provide a small, compact, readily portable cooler, gasser and dispenser for keg beer and the like which will assure excellent draught characteristics of the beverage, a desired uniform temperature and uniform gassification during consumption of the entire contents of the keg.

A further object is the provision of a device of the class described wherein a simple, compact wheeled chassis serves the multiple functions of a keg-support, a refrigerating chamber, a mounting for controlled gassing and dispensing mechanism and in addition, a valuable source of advertising for the distributor or manufacturer of the beverage.

Another object is to provide a compact, rugged device of the class described of simple and inexpensive construction affording a high degree of sanitation and provision for sterilizing of the few dispensing parts.

These and other objects and advantages of my invention will more fully appear from the following description made in conjunction with the accompanying drawings in which like reference characters refer to similar parts throughout the several views thereof, and in which:

Fig. 1 is a rear elevation of an embodiment of my invention showing a keg of beer installed within the multi-purpose chassis with the operating mechanism of the device properly connected for dispensing the beer on draught and for controllably gassing the same;

Fig. 2 is a side elevation of the same; and

Fig. 3 is a front elevation of my device showing the convenient location of the dispensing tap and the handhold for manipulating and moving the chassis and also, showing the favorable location of a large advertising space at the front of the chassis.

In the embodiment of my invention illustrated, a multi-functional, chassis body is employed preferably in the

2

form of an integral housing indicated as an entirety by the numeral 5 and having a lower, open topped, cylindrical chamber-forming portion 5a and a supporting bottom 5b. The housing 5 as shown, has an integrally formed, upstanding portion 5c which rises a considerable distance above the chamber-forming portion 5a and preferably is defined at its side edges by reversely curved lines merging into the rear of the lower portion 5a and likewise merging into a horizontal, arcuate edge 5d at the upper and forward terminal of the housing. The entire housing may be conveniently constructed from a suitable cylindrical drum having a bottom therein, by cutting along the lines from top to an intermediate rear portion, as clearly indicated in the three figures of the drawing.

15 The exposed edges of the open top of the housing including the side edges, upper edge and lower edge defining the top portion of the rear of the compartment-forming section, are preferably covered by a continuous trim 6 of compressible cushioning material such as split rubber tubing, cemented to the curved edges previously referred to.

The housing 5 at least in the lower chamber-forming portion 5a thereof, is of a cross sectional shape substantially larger than the maximum cross sectional area of a keg or other container to be housed and supported therein, thereby leaving when the keg or container is supported centrally upon the bottom of the housing, an annular cooling chamber which may be filled with ice or other suitable refrigerant, as indicated in dotted lines in

30 Fig. 3.

The lower circumferential edge of the chassis body of housing is preferably provided with a cushioning trim 7 of split rubber tubing or the equivalent.

The chassis body at rest, is supported upon a pair of spaced wheels 8 preferably constructed of hard rubber or equivalent, non-abrasive material journaled on fixed axles 8a which are secured between the depending ends of a U-shaped bracket 9 in each instance. The brackets 9 and wheels 8 as shown, are disposed in spaced relation at the forward portion of the housing bottom and are axially aligned. At the opposite portion of the bottom, a suitable supporting stand 10 is provided, as shown in the shape of a U-shaped rod having the upper ends of its two legs welded or otherwise rigidly affixed to the housing bottom. The height of the stand is preferably approximately equal to the combined height of the wheels with their mounting brackets to maintain the chassis body upright with the bottom thereof disposed substantially horizontally. A water drain and cock 11 is mounted at the rear portion of the chamber section 5a near the bottom of the housing and of course, in communication with the interior thereof.

The upstanding portion 5c of the chassis body forms a wide supporting post and is provided with suitable handle means for facilitating ready tilting of the body from its normally resting erect position to place the weight upon the wheels 8 for wheeling of the chassis forwardly or rearwardly as desired. To this end, in the form illustrated, hand holds 5e are formed through the upper end of the upstanding housing post 5c and adjacent the longitudinal edges thereof; and the upper and horizontal edges defining these hand holds are preferably cushioned by suitable rubber trim 12.

The upstanding portion 5c of the chassis body further serves as a mounting and support for a detachably connected tap 13 which may be of conventional construction having the valve handle 13a and a conventional discharge spout 13b. Such a tap has an inner tubular portion externally threaded for attachment to a threaded socket 14, tapped through top central port of the upstanding chassis portion 5c.

The interior or rear wall of the upstanding chassis portion 5c functions as a medium for supporting and housing a carbon dioxide supply tank and its valved connections with the upper portion of a keg K. To this end, as shown, a heavy, resilient, split gripping collar 15 is secured to the intermediate rear surface of upstanding housing portion 5c, constructed to tightly grip and support a small compressed-gas tank G of conventional structure. For malt beverages such as beer and ale the gas medium is usually carbon dioxide, which is obtainable in small tanks highly pressurized, weighing as little as a pound or pound and one-half. The tank G is valved at its upper end and has affixed thereto a small gas discharge pipe 16 which is equipped with a regulator and gauge combination 17 and has further interposed therein, as shown, a cock 18. A conduit 19 which may be a flexible hose, connects cock 18 with a conventional tap rod R, which is tightly fitted into the bung hole of the keg after the bung is removed. As shown, a regulator and gauge combination 20 is interposed in the line of conduit 19.

The conventional tap rods mentioned employ a fitting having an annular or other passage for the gas through the shank thereof, said fitting surrounding and being out of communication with the elongated beer discharge pipe 21 which is affixed axially to the fitting and extends downwardly to a point close to the bottom of the keg. The upper end of beer discharge pipe 21 communicates with a discharge head 21a which is connected as shown by a "once used" or disposable hose section 22, the upper end of said section being engaged with the inlet pipe 13c of the tap 13 mounted forwardly and externally of the chassis body near the top thereof.

Operation and advantages

From the foregoing description it will be seen that I have provided a portable chassis which is adapted to normally stand in erect position with the bottom thereof supporting a keg or other container containing a draft beverage such as beer. Present day kegs are for the most part constructed of metal so that chilling of the contents by packing the annular space between keg and the lower housing portion 5a with ice is readily accomplished. The chassis body thus serves as a support for the keg and as a refrigeration compartment to receive ice and thus obtain uniform chilling of the contents of the keg.

The device may be readily wheeled from place to place by grasping the top part of the upstanding portion 5c of the housing and tilting the same slightly forward to place the weight of the keg and housing on the wheels 8.

After the keg is chilled the gas supply and its line is regulated at the proper predetermined pressure, and the beer or other beverage may be withdrawn as desired by actuating the tap 13, the discharge being disposed at a convenient height at the top portion and front of the chassis body.

A substantially uniform temperature of the beverage is secured through the cooling of the keg rather than the conventional dispensing coil. Therefore uniform

gassification of the beverage during consumption of the entire contents of the keg is assured, since the saturation level of the gas by the beverage is substantially constant.

The parts of my device or apparatus are few, being 5 with exception of the unique multi-functional chassis of conventional structure which can be easily obtained from present manufacturers.

While obtaining new and superior results in the uniform and excellent draft characteristics of the beverages 10 served, my device adds no additional media such as elongated coils or other parts which are difficult to sterilize. The tap 13 is readily removable from the chassis for sterilization, as is the conventional tap rod R.

My improved device is particularly adapted for use at 15 small gatherings where it is desired to portably support, chill, gas and dispense malt beverages and the like to a number of people at different points in a room or suite of rooms or in a yard.

The front of the chassis body offers an excellent medium 20 of advertising for a manufacturer or distributor, being disposed directly below the tap from which the beverage is withdrawn.

It will of course be understood that various changes 25 may be made in the proportions and arrangements of the parts and in the substitution of equivalents all within the scope of my invention.

What I claim is:

1. Apparatus for cooling, gassing, transporting and dispensing keg beverages comprising a chassis body entirely open at its upper end and in the form of a housing having a bottom and cylindrical lower chamber of a cross sectional shape larger than that of a keg to be accommodated to provide an annular ice-packing space, said chamber being of a mean height less than that of the 35 height of the keg to be accommodated therein said body being continuous and having an upwardly tapered, upstanding supporting post rising substantially above said chamber portion and above a keg mounted upon the bottom of said body, a dispensing tap mounted exteriorly 40 at the top of said upstanding post, means for detachably supporting a small tank of charging gas on the interior of said upstanding supporting post, a conventional gas-discharging and beverage withdrawal tap for positioning in the bung-hole of a beverage keg, regulating valve connections for connection between said gas-charging tank 45 and said keg tap and means connected with the lower portion of said body for facilitating travel of said body over the ground or other supporting surface.

2. The structure set forth in claim 1 and said last mentioned means constituting a pair of wheels below one side of the bottom of said body and a supporting stand below the opposite side of said body.
